(57) **CLAIM**

The ornamental design for a tobacco pipe as shown and described.

DESCRIPTION

1. Tobacco pipe
A non-electric and non-electronic tobacco pipe; FIG. 1.1 is a front perspective view thereof; FIG. 1.2 is a top view; FIG. 1.3 is a bottom view; FIG. 1.4 is a left view thereof; FIG. 1.5 is a right view thereof; FIG. 1.6 is a front view thereof; FIG. 1.7 is a front perspective view thereof showing the tobacco pipe drawer in an extracted position, which is apt to contain a dose of tobacco.

The broken lines in the drawings depict portions of the tobacco pipe that form no part of the claimed design.
